ABSTRACT OF THE DISCLOSURE

A tank valve apparatus particularly adapted for effecting rapid discharge of the liquid contents of a tanker truck or the like by reason of its location substantially out of the path of liquid flow, the valve being oriented interiorly of the tank and movable inwardly to a discharge position by toggle arms actuatable by levers which are pivotable from the exterior of the tank.

BACKGROUND OF THE INVENTION

Field of the invention

The invention relates to the field of discharge valve apparatus for a tank, and particularly for use with a tanker truck or the like of the type commonly used for transporting bulk gasoline or other liquid, the valve being externally operable to empty the contents of the tanker truck when it has reached its destination.

Description of the prior art

Existing valves for tanker trucks and the like are characterized by operating components which are located directly in the path of flow of the liquid during discharge. This partial blocking or disruption of the liquid flow greatly slows what should be a rapid discharge operation.

SUMMARY OF THE INVENTION

According to the present invention, the tank valve apparatus is characterized by a valve mounting and operating mechanism which is located interiorly of the tank to be emptied, and in spaced relation to the discharge opening normally closed by the valve of the apparatus. The valve apparatus includes a pair of support elements of relatively small cross section which extend into the tank for some distance and support toggle arms which are pivotally connected to the stem of the valve. Operation of the toggle arms raises the valve away from the discharge opening and out of the path of the liquid being emptied, only the relatively small area of the support elements being in the path of the discharging liquid. Thus, the tank can be rapidly emptied by reason of the small portion of the valve apparatus which blocks its path.

The valve apparatus is quickly attachable to existing tanker trucks, is relatively inexpensive to manufacture, is reliable in operation, and can be quickly removed for adjustment and maintenance.

Other objects and features of the invention will become apparent from consideration of the following description taken in connection with the accompanying drawings.

BRIEF DESCRIPTION OF THE DRAWING

FIG. 1 is a top plan view of the tank valve apparatus of the present invention; as the same would be viewed from the interior of a truck tank in which it is installed;

FIG. 2 is a view taken along the line 2—2 of FIG. 1, and showing the arrangement of the toggle arms in the closed position of the valve;

FIG. 3 is a view taken along the line 3—3 of FIG. 1; FIG. 4 is a view similar to FIG. 2 but limited pri-

2

marily to a showing of the arrangement of the toggle arms in the open position of the valve;

FIG. 5 is a view taken along the line 5—5 of FIG. 1; and

FIG. 6 is a view taken along the line 6—6 of FIG. 2.

Referring now to the drawings, there is illustrated a tank valve apparatus 10 which is adapted to effect rapid discharge of the liquid contents of a tank such as the tank of a tanker truck or the like. The apparatus 10 is illustrated as it would appear when mounted to the edge margins of an opening 12 in the bottom 14 of such a tank.

The apparatus 10 includes a mounting assembly 16 having an annular outer ring 18 which is welded or otherwise secured to the edge margins of the tank opening 12. The assembly 16 also includes an annular inner ring 20 which fits within the central opening in the outer ring 18 and is characterized by a peripheral flange 22 which abuts against the underside of an adjacent portion of the outer ring 18. An annular sealing ring or gasket 24 is interposed between the outer and inner rings 18 and 20 to provide a liquid-tight seal.

The central opening in the inner ring 20 defines a discharge opening 25 which terminates at its inner extremity in a tapered valve seat 26.

The inner ring 20 is securely fastened to the outer ring 18 by a plurality of fastener assemblies disposed in spaced relation about the periphery of the rings, each such assembly including a threaded stud 28 which is threaded into a suitable opening in the underside of the outer ring 18, an anchor lug 30 axially slidably carried by the stud 28 and engaging the undersides of the inner and outer rings, and a nut 32 threaded upon the stud 28 and engaging the underside of the lug 30. Tightening of the nuts 32 detachably clamps the inner ring 20 to the outer ring 18 in sealing relation. As will be seen, removal of the nuts 32 permits the inner ring 20 and the components mounted thereon to be quickly dissociated from the tank bottom 14.

A similar plurality of fastening assemblies secures an annular adaptor collar 34 to the underside of the inner ring 20, the central opening in the collar 34 constituting a continuation of the discharge opening 25 of the inner ring 20. The collar 34 is adapted to be clamped to a discharge conduit (not shown) for carrying away the liquid discharged from the tank. In this regard, the fastening assemblies securing the collar 34 to the inner ring 20 can be quickly operated to permit different sizes of collar 34 to be installed for coupling to different sizes of discharge conduit.

For this purpose, each of the fastening assemblies includes a stud 36 threaded into the underside of the inner ring 20 and threadably mounting a nut 38 which presses against a lug 40 having a radially inwardly extending portion which engages the underside of a peripheral flange 42 of the collar 34. A sealing ring or gasket 44 is interposed between the collar 34 and the inner ring 20 to provide a liquid-tight seal.

A circular valve 46 is disposed over the discharge opening 25 and includes an annular sealing ring 48 which rests upon the valve seat 26 to provide a liquid-tight seating arrangement. The valve 46 includes a central opening which slidably receives an inwardly and vertically oriented valve stem 50, the valve 46 being retained on the valve stem 50 by a nut 52 threadably mounted to the lower threaded extremity of the valve stem 50.

The upper extremity of the valve stem 50 is also threaded and mounts an adjusting nut 54 and a lock nut 56, the position of the adjusting nut 54 determining the vertical position of a coupling assembly 58 which is vertically slidably mounted upon the upper extremity of the valve stem 50. As best viewed in FIG. 5, the coupling assembly 58 includes a pair of horizontally oriented,

vertically spaced-apart guide elements 60 which have vertically aligned openings which slidably receive the valve stem 50. The guide elements 60 are secured together at their opposite sides by a pair of side plates 62 which are welded to the elements 60, and which extend along opposite sides of the valve stem 50.

The pair of side plates 62 pivotally mount the inner or upper extremities of a pair of elongated, parallel, and spaced-apart links constituting a toggle arm 64, and similarly mount a pair of identical links constituting a toggle arm 66. As will be seen, upward movement of the inner extremities of the toggle arms 64 and 66 is effective to raise the coupling assembly 58 and thereby raise the valve 46 off its seat 26, whereas downward movement of the inner or upper extremities of the toggle arms 64 and 66 is effective to move the coupling assembly 58 downwardly, thereby allowing the valve 46 to move downwardly onto its seat 26.

As best viewed in FIGS. 2, 3, and 6, the lower or outer extremities of the links constituting the toggle arms 64 and 66 are pivotally mounted, respectively, to a pair of trunnions 68 and 70. Each trunnion 68 and 70, in turn, forms a part of the associated one of a pair of actuators 72 and 74.

More particularly, the actuator 74 is characterized by a pair of laterally and diametrically oppositely extending arms 76, one of which mounts a vertically disposed pivot pin 78 which secures the trunnion 70 in position for pivotal movement about the vertical axis of the pin 78. As best seen in FIG. 6, the trunnion 70 includes a pair of lateral extensions which mount the parallel links of the toggle arm 66 for pivotal movement thereof in parallel vertical planes.

The portion of the actuator 74 located centrally of the pair of arms 76 includes a central opening which receives the upper extremity of a torque rod 82 which constitutes a part of an elongated, vertically and inwardly extending support element 84. The rod 82 is slidably fitted within the hollow interior of a support sleeve 86 which also constitutes a part of the element 84. The actuator 74 is retained in position upon the torque rod 82 by a nut 88 which is threaded onto the threaded upper end of the rod 82. The nut 88 bears against a washer 90 which rests upon the actuator 74, and a washer 92 is interposed between the underside of the actuator 74 and the upper end of the support sleeve 86 to facilitate pivotal movement of the actuator 74 relative to the sleeve 86. The washer 92 also rests against an upper adjustment nut 94 which is threaded onto the threaded upper extremity of the support sleeve 86.

It is particularly noted that the upper extremity of the torque rod 82 is provided on opposite sides with a pair of flats 96 which engage corresponding flats (not shown) forming a part of the central opening in the actuator 74. Thus, rotation of the torque rod 82 engages the flats 96 with the flats of the opening in the actuator 74, and thereby rotates the actuator 74.

The lower extremity of the support sleeve 86 is threadably mounted within a suitable opening provided in the inner ring 20, the sleeve 86 extending only about halfway into this opening. However, the torque rod 82 projects below the lower terminus of the sleeve 86 and below the lower surface of the inner ring 20. A short collar 98 is disposed over the projecting lower end of the torque rod 82 and a pair of sealing washers 100 are interposed between the adjacent ends of the collar 98 and the sleeve 86 to provide a liquid-tight seal.

The lower end of the torque rod 82 is provided with a pair of flats 102 which engage complementary flats (not shown) characterizing the central opening of an end portion 104 of an operating arm 106. The end portion 104 is held in position on the threaded lower end of the torque rod 82 by a nut 108, the nut 108 being tightened sufficiently to maintain the liquid-tight relation between the support sleeve 86 and the collar 98.

As best viewed in FIG. 1, the operating arm 106 is pivotally coupled to one end of an elongated linkage 110 which is reciprocable by any suitable means to effect rotation of the torque rod 82. That is, the linkage 110 can be mechanically operated by a suitable hand lever (not shown), or may be coupled to an air cylinder or the like for operation. In either event, as will be seen, actuation of the linkage 110 is effective to rotate the torque rod 82 which initiates seating and unseating of the valve 46.

The trunnion 68 opposite the trunnion 70 is mounted by a vertical pin 112 to a laterally extending arm 114 of the actuator 72 for pivotal movement about the vertical axis of the pin 112. As best seen in FIG. 3, the actuator 72 includes a central opening which receives a tubular sleeve or bearing 116 which rotatably receives the threaded shank of a bolt 118. The lower end of bolt 118 is threaded into the upper end of an elongated, inwardly and vertically oriented support rod 120 which forms a part of a support element 122 located on the side of the valve stem 50 opposite the support element 84. The support rod 120 is slidably fitted through the hollow interior of an elongated support sleeve 124 which also constitutes part of the support element 122. The upper end of the support sleeve 124 is threaded to receive an upper adjustment nut 126, and the lower extremity of the support sleeve 124 is threadably disposed within an opening in the inner ring 20, extending approximately halfway into the opening.

The support rod 120 extends below the lower end of the support sleeve 124 and is surrounded by an annular gasket 128. The support rod 120 is secured to the sleeve 124 by a bolt 130 which is threaded into an opening in the lower end of the rod 120, the head of the bolt 130 bearing against a pair of sealing washers 132 and 134 to afford a liquid-tight seal between the sleeve 124 and the inner ring 20.

An elongated tie member 136 is pivotally connected at its opposite extremities to the arm 114 of the actuator 72 and to the arm 76 of the actuator 74 which is opposite the arm 76 to which the trunnion 70 is pivotally secured. With this arrangement, pivotal movement of the actuator 74 is transmitted to the actuator 72 so that both actuators move in common.

A circular skirted spring retainer 138 is disposed across the valve stem 50 and support elements 84 and 122, including a central opening 140 which loosely receives the valve stem 50 to allow free movement of the valve stem 50 relative to the spring retainer 138. In addition, the retainer 138 includes a pair of openings on opposite sides of the opening 140 to receive the support sleeves 86 and 124, the upper surface of the retainer 138 bearing against the undersides of the upper adjustment nuts 94 and 126. A pair of lower adjustment nuts 142 and 144 are threaded onto the support sleeves 86 and 124, respectively, and bear against the underside of the transverse portion of the spring retainer 138 to clamp it in position. The adjustment nuts may be threaded upwardly or downwardly upon their associated support sleeves in order to adjust the vertical position of the spring retainer 138.

The adjustment and vertical position of the spring retainer 138 adjusts the bias of a compression spring 146 which is disposed about the valve stem 50 and which has its opposite ends in abutment with the spring retainer 138 and the valve 46. With this arrangement, the spring 146 tends to bias the valve 46 to its closed position, that is, seated upon the valve seat 26. The spring retainer 138 also functions to rigidify the support elements 84 and 122 during operation of the tank valve apparatus 10.

In operation, and assuming the tank with which the apparatus 10 is associated is to be discharged, a suitable discharge conduit (not shown) is coupled to the collar 34. Next, the linkage 110 is moved in the direction of the arrow shown in FIG. 1 to thereby pivot the torque rod

82. As viewed in FIG. 1, this pivots the actuator 74 in a counterclockwise direction to thereby move the lower or outward extremity of the toggle arm 66 inwardly. In addition, the tie member 136 is acted upon by the actuator 74 to also pivot the actuator 72 in a counterclockwise direction, causing the lower or outward extremity of the toggle arm 64 to move inwardly.

The inward movement of the lower extremities of the toggle arms 64 and 66 causes the upward extremities of the toggle arms to move the coupling assembly 58 upwardly, which moves the valve 46 upwardly to its discharge position against the bias of the spring 146.

The liquid in the tank then has a relatively unimpaired flow path from the tank and through the discharge opening 25, the only impediment to the liquid flow being the relatively small cross section of the support sleeves of the pair of support elements 84 and 122.

Closure of the valve 46 is quickly effected by movement of the linkage 110 in the direction opposite the arrow shown in FIG. 1. This movement has the effect of causing the actuators 72 and 74 to move in a counterclockwise direction. The lower extremities of the toggle arms 64 and 66 move outwardly, and the upper extremities of the toggle arms move downwardly, thus permitting the bias of the spring 146 to urge the valve 46 to its closed position.

From the foregoing it will be apparent that a tank valve apparatus 10 has been provided which is readily adapted for association with existing tanker trucks. The apparatus 10 is substantially wholly contained within the tank and is easily operable from the exterior of the tank either manually or by air or hydraulic cylinders or the like. Most importantly, the arrangement of toggle arms located out of the path of liquid flow permits the valve to be easily operated without significant interference with rapid liquid discharge.

Various modifications and changes may be made with regard to the foregoing detailed description without departing from the spirit of the invention or the scope of the following claims.

I claim:

1. A tank valve apparatus comprising: mounting means adapted for securement adjacent the edge margins of an opening in a tank bottom, said mounting means defining a discharge opening having a valve seat; a valve on said seat for closing said discharge opening and including an elongated valve stem extending vertically and inwardly of the tank; a pair of elongated, vertically oriented support elements located on opposite sides of said valve stem and secured at their lower extremities to said mounting means; a pair of actuators pivotally mounted to the upper extremities of said support elements, respectively, and including actuator arms movable toward and away from said valve stem upon pivotal movement of said actuators; a tie member pivotally coupling together said actuator arms for common movement; a pair of elongated toggle arms pivotally mounted at their outer extremities to said pair of actuator

arms, respectively; coupling means pivotally mounting the inner extremities of said toggle arms to the upper extremity of said valve stem; and operating means coupled to one of said actuators and operable to pivot said actuator in one direction to move the outer extremities of said toggle arms inwardly to raise said valve stem and said valve to a discharge position; and operable to pivot said actuator in the opposite direction to move the outer extremities of said toggle arms outwardly to lower said valve stem and said valve to a closed position.

2. A tank valve apparatus according to claim 1 wherein one of said support elements is hollow, and said operating means includes an elongated torque rod extending through said one of said support elements, connected at its upper extremity to the adjacent one of said actuators, and projecting outwardly of said mounting means at its lower extremity whereby said torque rod is adapted to be rotated in opposite directions for opening and closing said valve.

3. A tank valve apparatus according to claim 1 and including spring retainer means mounted to said support elements; and a compression spring interposed between said spring retainer means and said valve and tending to bias said valve to a closed position.

4. A tank valve apparatus according to claim 3 wherein said spring retainer means includes adjustment elements for mounting said spring retainer means to said support elements at various points along the lengths of said support elements to thereby vary the bias of said spring against said valve.

5. A tank valve apparatus according to claim 1 wherein said coupling means is adjustably mounted to the upper extremity of said valve stem for adjustment of the vertical position thereof on said valve stem to thereby adjust the position of said valve in its closed position and insure firm seating of said valve on said valve seat.

6. A tank valve apparatus according to claim 1 wherein said mounting means includes an outer ring for attachment to the tank bottom; an inner ring defining said discharge opening and mounting said support elements; and a plurality of mounting fasteners securing said inner ring to said outer ring, said fasteners being demountable for dissociation of said inner ring and its associated components from the tank.
